THOMAS J. KING, JR., OF CHICAGO, ILLINOIS, ASSIGNOR TO THE GERRARD COMPANY, INC., OF CHICAGO, ILLINOIS, A CORPORATION OF DELAWARE

DEVICE FOR SUPPORTING WIRE TYING MACHINES

Application filed November 23, 1927. Serial No. 235,136.

In shipping a number of massive units, such as barrels, boxes, crates, machines, and the like, it is advisable to wire the same together in a horizontal plane, otherwise, in starting and stopping, the units are apt to shift relative to each other, with the possibility of serious damage.

Heretofore it has not been feasible to use an ordinary portable wire tying machine in applying the wire, since such a machine is only designed to tie a wire which is arranged in a vertical plane, and, in wiring massive units together for transportation, the wire must be arranged in a horizontal plane.

The primary object of the invention is to provide means in the form of a novel machine-supporting device for permitting a portable machine to be used conveniently in tying a wire in a horizontal plane.

Other objects and advantages of the invention will be apparent to those skilled in the art upon a full understanding of the construction, arrangement and operation of the device.

One form of the invention is presented herein for the purpose of exemplification, but it will of course be appreciated that the invention may be embodied in other structurally quite different forms coming equally within the scope of the appended claims.

In the accompanying drawings:

Fig. 1 shows a wire-tying machine supported by the device of the invention in operative position to a number of barrels;

Fig. 2 is a horizontal section through the rack, taken on the line 2—2 of Fig. 1;

Fig. 3 is another horizontal section through the rack, taken on the line 3—3 of Fig. 1;

Fig. 4 is a vertical section through the rack, taken on the line 4—4 of Fig. 1, showing the wire-tying machine in threading position; and

Fig. 5 is a view corresponding to Fig. 4, showing the machine in tying position.

The drawings illustrate a number of barrels 10 which have been bound together by wires 11 tied by a portable wire tying machine 12 while mounted on a rack 13. The invention resides in the support for the machine, which support includes the rack 13

and a pair of hooks 14 on the machine which cooperate with the rack and hold the machine in first a horizontal and then a vertical position.

The wire-tying machine shown in the drawings is the same as that which is illustrated, described and claimed in my co-pending application, Serial No. 235,135, filed November 23, 1927, but such machine is used herein merely for the purpose of exemplification, and it will of course be understood that other kinds of wire-tying machines may be supported in the same manner.

The rack 13 consists of two upright standards 15 which are mounted on two outspread bases 16. The standards are connected together by one or more cross members 17 which are offset rearwardly with respect to the standards by brackets 18. The brackets, with the cross members, are vertically adjustable with respect to the standards, being held in any desired position by set screws 19 which are carried by the brackets and are screwed into frictional engagement with the standards. The standards are preferably angle members, while the cross members are preferably flat strips lying in a vertical plane.

The hooks 14 are pivoted at 20 to the rear portion of the base 21 of the machine, in longitudinally spaced relation to each other, and are provided with elongated slots 22 into which either one of the cross members 17 will snugly fit. The hooks are adapted to hold the machine in either the horizontal threading position shown in Fig. 4, or the vertical tying position shown in Fig. 5, the horizontal arrangement shown in Fig. 4 being effected by means of two latches 23 which are pivoted to the machine at 24 and are adapted to engage with abutments 25 on the hooks, thereby holding the machine with the base of the same in perpendicular relation to the slots 22 in the hooks. When the latches 23 are released, by pressure applied to the ends 26 thereof, the machine will swing downwardly about the pivot 20 into the vertical position shown in Fig. 5.

In applying a wire to the barrels, the barrels are grouped snugly together, the rack 100

is positioned adjacent one side of the same, and the machine is mounted on the rack in the horizontal position shown in Fig. 4.

The wire is then passed around the barrels, threaded through the machine, and partly tensioned by operation of the handle 27 in order to hold the wire in place.

When the machine is in readiness to tie the wire, the latches 23 are tripped to drop the machine into the position shown in Fig. 5, whereupon the tensioning, twisting and cutting operations are effected in the ordinary way, as if the machine were on the top, instead of against the side, of the object being wired. After the wire has been tied, the machine is unhooked from the cross member 17 by being moved in a vertical direction, and the rack is moved away. Because of the offset relation between the cross members 17 of the rack and the standards 15, the wire is tied about the barrels behind the standards 15, and no interference therebetween is had.

It will be observed that in the preceding specification and following claims the machine is referred to as a "wire-tying" machine. This language is of course intended to include within its meaning all known types of portable machines for applying binding material, regardless of whether the wire is round or flat and irrespective of whether the tie is a twist, an interlocking deformation, or a sleeved seal.

I claim:

1. The combination, with a portable wire-tying machine, of a rack for holding the machine adjacent the side of the object to be tied, and means carried by the machine and detachably associated with the rack for holding the machine in two different positions with respect to the rack and to the side of the object to be tied.

2. The combination, with a portable wire-tying machine, of a rack for holding the machine adjacent the side of the object to be tied, and means carried by the machine and detachably associated with the rack for holding the machine in either a horizontal or vertical position with respect to the rack and to the side of the object to be tied.

3. The combination, with a portable wire-tying machine, of a rack for holding the machine against tilting movement in a position adjacent the side of the object to be tied, said rack including an upright portion, and a rearwardly offset holding portion.

4. The combination, with a portable wire-tying machine, of a rack for holding the machine adjacent the side of the object to be tied, a hook for detachably supporting the machine on the rack, and readily releasable means for preventing the machine from turning in one direction with respect to the rack.

5. The combination, with a portable wire-tying machine, of a rack for holding the ma-

chine adjacent the side of the object to be tied, a hook pivoted to the machine in rigid engagement with the rack for supporting the machine in either a horizontal or vertical position, and a latch carried by the machine for engaging with the hook and holding the machine in a horizontal position.

6. The combination, with a portable wire-tying machine having a flat outspread base, of means for holding the machine with the base of the same in a vertical position parallel with a vertical side of the object to be tied to permit the tying of a horizontally looped wire.

7. The combination, with a portable wire-tying machine, of a portable support for holding the machine in an elevated operative position adjacent a vertical side of the object to be tied, and a readily releasable connection between the machine and the support, said connection being operable to hold the machine in an outwardly projected position with respect to the support and being releasable upon vertical movement of the machine relative to the support.

8. The combination, with a portable wire-tying machine, of a rack for holding the machine adjacent the side of the object to be tied, and a hook carried by the machine in engagement with the rack, said hook having a downwardly opening throat portion shaped to interfit non-rotatably with a portion of the rack.

In testimony whereof I have hereunto subscribed my name,

THOMAS J. KING, JR.
